UNITED STATES PATENT OFFICE.

AUSTIN H. HART, OF GREENWICH, CONNECTICUT, ASSIGNOR TO ROME RADIATION COMPANY, INCORPORATED, OF ROME, NEW YORK.

STREAM-LINE HIGH-PRESSURE RADIATOR.

Application filed November 9, 1926. Serial No. 147,353.

This invention relates to improvements in heat exchange devices of the radiator type in which a plurality of sections are provided with apertures and are suitably connected to 5 form built-up heating units of any desired size.

Radiators now in common use are not adapted for use in heating systems requiring a working pressure in excess of fifty pounds. 10 Where higher temperatures than those available from radiators incapable of withstanding pressures beyond fifty pounds, are required, it has been necessary heretofore to resort to coils of piping capable of withstanding the increased pressures involved 15 in obtaining the higher temperatures.

The object of the present invention is to overcome this disability of the radiator type of heaters, by providing sections 20 shaped and reinforced by heat radiating fins so as to adapt these sections and the units built therefrom to operate at any desired pressure and temperature.

Other objects of the invention will appear 25 as the detailed description thereof proceeds.

In the drawing,

Fig. 1 is an end elevation of a radiator section constructed in accordance with my invention.

30 Fig. 2 is a side elevation of the same. Fig. 3 is a plan view of the said section.

As shown in the drawing, the radiator section is made up of a pair of plates 1 and 2 of sheet metal, preferably brass, suitably 35 secured together at their edges 3 and 4, as by electric welding to form a conducting passageway for the heating fluid circulating through the radiator.

The sheets of each section are so shaped 40 that when they are secured together, they form a section having one end 5 thereof semi-cylindrical and with the sides extending therefrom and tapering gradually to meet in a sharp straight edge 6. Each end of a 45 section is provided with the usual bushing inserts 7 set in each section as closely as possible to the cylindrical end of the section.

In order to provide additional radiating 50 surfaces, each radiator section is provided

with a plurality of heat radiating fins 8, completely encircling a section and provided with flanges 9 extending at right angles to the body of each fin. As clearly shown at Fig. 3 each fin 8 is stamped out to fit with 55 a snug friction fit over the central parts of the section. The flanges 9 keep the fins 8 always perpendicular to the surfaces of the sections 1 and consequently prevent the fins 8 from buckling when pressure is applied to 60 the inside of the section.

The bushings 7 are set in each end part 10 as closely as practicable to the cylindrical end 5 in order to feed the heating fluid directly to the larger end of the section. In 65 order to strengthen the end parts 10 which for obvious reasons cannot be provided with the reinforcing fins 8, these parts are curved sharply inward from the edge 6 to extend concentrically around their bushings 7. 70

It will be obvious from the drawing that these fins 8 not only greatly increase the heat radiating areas of the sections but also serve as strong reinforcing bands which adapt the sections for use at any desired pressure and temperature, and thereby obviate the necessity for using pipe coils for heating purposes requiring pressures of greater than fifty pounds. It will be further obvious that the greater the pressure in each section, 75 the more tightly will the fins be held at their positions thereon.

Having thus described my invention, what I claim as new and desire to secure by United States Letters Patent is:— 80

A radiator section for heating systems adapted to be subjected to pressures above fifty pounds and comprising a pair of brass plates having their edges welded together and shaped to form, when so welded, a flat 90 tube with substantially parallel side walls and closed ends, and a plurality of fins spaced apart lengthwise on and supported wholly by said tube, each fin being provided with a flange shaped to contact in close 95 sliding friction fit with the periphery of said tube and adapted to hold its fin perpendicular to said tube.

In testimony whereof I affix my signature.
AUSTIN H. HART.
